UNITED STATES PATENT OFFICE.

WILLIAM H. RAPP, OF READING, PENNSYLVANIA.

TRAY.

1,010,801.

Specification of Letters Patent. Patented Dec. 5, 1911.

Application filed December 22, 1910. Serial No. 598,851.

To all whom it may concern:

Be it known that I, WILLIAM H. RAPP, a citizen of the United States, and a resident of the city of Reading, in the county of Berks and State of Pennsylvania, have invented certain new and useful Improvements in Trays, of which the following is a specification.

My invention relates particularly to trays adapted to be conveniently piled or stacked one upon another, and employed for various purposes such for instance as the manufacture of confections; and it consists essentially in the improved corner-construction provided for, as hereinafter fully described in connection with the accompanying drawings and specifically pointed out in the claims.

Figure 1 is a perspective view of a tray embodying my invention. Fig. 2 is an enlarged cross-sectional view taken on the line 2—2 of Fig. 1, indicating also the manner of stacking the trays one upon another. Fig. 3 is a cross-sectional view on the diagonal line 3—3 of Fig. 1, showing the sealing material in the corner thereof. Fig. 4 is a separate view of a corner piece, showing a slight modification of the form illustrated in the other figures. Fig. 5 shows the sheet-metal piece employed to form the tray illustrated.

As shown in the drawings, the bottom 2 and side walls 3, 3 of the tray are formed from a single piece of sheet metal of rectangular shape; the corners of said blank being cut away as shown so that the upturned edge portions forming the walls 3 have their meeting ends 3^a 3^a slightly separated, instead of attempting to form a tight corner-connection thereof. At each corner of this pan I provide an angle-iron corner-piece, the angled flanges or arms 5, 5 of which are rigidly secured to the adjacent meeting ends 3^a 3^a of the side walls, by rivets 6 as shown. This corner piece has its arms extended at one end above said side walls 3, such extensions 5^a 5^a being in the planes of the arms 5, 5, and it is also extended at the other end, below the tray bottom 2, an off-set 5^b being here formed however so as to throw the lower arm extensions

5^c 5^c into different planes, parallel with the arms 5, 5 as shown, and thus provide an angular off-set shoulder 5^d; which shoulder is adapted to serve as a supporting seat for 55 the opposite extensions 5^a 5^a of a mating tray as hereinafter described. The off-set 5^b may extend either inward, or outward (as indicated in Fig. 4), to form this supporting shoulder 5^d in connection with the guide extensions 5^c 5^c; but when extended inward as indicated in Figs. 1, 2 and 3, so that the upper shoulder 5^d of the off-set may seat against the bottom of the tray as shown, this off-set serves the further purpose of assisting in the forming of a tight joint at the junction of the separated meeting ends 3^a 3^a of the side walls 3, 3 of the tray, as provided for in the construction shown. This is accomplished by filling the small space 70 naturally formed between the separated edges of these meeting ends 3^a 3^a, with a suitable sealing material 10, which is supported upon said off-set and securely locked between the separated edges so as to form a 75 permanently tight corner. As indicated in Fig. 2 these corner pieces provide for quickly and properly stacking or piling the trays one upon another, with a determined spacing between the confections or other material placed thereon; the top extensions 5^a 5^a loosely engaging the off-set bottom extensions 5^c 5^c of a superposed tray and the angular shoulder 5^d of the latter seating upon the ends of said extensions 5^a 5^a as shown. 80

What I claim is:

1. A tray having angularly arranged vertical walls, and exteriorly applied angle-iron corner pieces the angled-plates of each of which are attached intermediately of 90 their length to adjacent meeting ends of said walls and have their opposite ends extended respectively above and below said walls; the extended portions of the angled-plates at one end being off-set to form an angular seating shoulder for the overlapping opposite extension of a meeting-tray corner piece, substantially as set forth.
2. A tray having a sheet metal bottom plate having upturned edge-portions with 100 separated meeting ends; exteriorly applied angle-iron corner-pieces connecting said

meeting ends and extended above and below the tray, the lower extension of each corner-piece being offset to form an inner shoulder against the tray bottom and an outer seating shoulder for a mating tray; and sealing material between said meeting ends and the shouldered corner-piece.

In testimony whereof, I affix my signature, in the presence of two witnesses.

WM. H. RAPP.
